UNITED STATES PATENT OFFICE

RENE TRICARD, OF PARIS, FRANCE, ASSIGNEE TO LENTHERIC INCORPORATED, OF
NEW YORK, N. Y., A CORPORATION OF NEW YORK

DESIGN FOR A LIP STICK CASE

Application filed May 12, 1933. Serial No. 48,090. Term of patent 14 years.

To all whom it may concern:

Be it known that I, RENE TRICARD, a citizen of France, residing at Paris, France, have invented a new, original, and ornamental Design for a Lipstick Case, of which the following is a specification, reference being had to the accompanying drawing, forming a part thereof.

In the drawing of the lipstick case:

I claim:

The ornamental design for a lipstick case substantially as shown.

RENE TRICARD.
